Atty.

UNITED STATES PATENT OFFICE.

JAMES MACDONNELL, OF HAVERHILL, MASSACHUSETTS.

CIGARETTE-FORMER.

1,385,018.

Specification of Letters Patent. Patented July 19, 1921.

Application filed April 28, 1919, Serial No. 293,059. Renewed June 7, 1921. Serial No. 475,835.

To all whom it may concern:

Be it known that I, JAMES MACDONNELL, a citizen of the United States, and a resident of Haverhill, county of Essex, State of Massachusetts, have invented an Improvement in Cigarette-Formers, of which the following is a specification.

This invention relates to devices for assisting in the formation of cigarettes by hand, and particularly to that class of devices which are adapted to be carried in the pocket conveniently and with which only one cigarette may be formed at a time.

The object of my invention is to provide a device of the above described character with which a cigarette may be easily and quickly formed of tobacco which is finely divided, as well as with that in which the fibers are long, and with which the tobacco may be thoroughly compressed, so that a solid cigarette may be produced. Also to provide a device for this purpose which is of simple construction, so that it may be manufactured at small expense and so that but little skill is required in its operation.

I accomplish these objects by the means shown in the accompanying drawing in which:—

Figures 1 and 2 are, respectively, side and end elevations of a cigarette former embodying my invention.

Figs. 3 to 6 are cross sectional views illustrating different steps in the cigarette forming operation.

Figs. 7 and 8 are perspective views showing the parts in positions similar to that of Figs. 3 and 6 respectively.

As shown in the drawing, the former is composed of two mold sections, *a* and *b* of concave form on their inner side and connected at their longitudinal edges by a hinge *c*, so that, when folded together, they will form a cigarette of the desired shape. The section *a* is provided with end walls *d* and *e* and the section *b* with similar end walls, *f* and *g*, so arranged that each end wall overlaps the opposite end wall in all positions of the sections, so that the mold will be closed at its ends when open, as well as when closed.

The end wall *g*, on the section *b*, is provided with a transverse ear *g'*, to which a concave section member *h*, of thin metal, is connected by a pivot *i'*, in such a position that the member will swing edgewise to and from the adjacent edge of section *b*, and the

opposite end wall *f* is provided with a clip *j* arranged to receive the opposite end portion of the member *h*, from its pivoted end, so that, when the latter is swung down into said clip it will form, with the section *b*, a complete mold section similar to the section *a*, the member *h* being formed slightly concavo-convex, as shown.

In operating the device to form a cigarette, the member *h* is swung upward out of its clip, as indicated in Fig. 7, and a cigarette paper *w*, the length of which is equal to the distance between the end walls *e* and *d*, is laid over the sections *a* and *b*, so that it extends beyond the edges thereof, as in Fig.

3. The member *h* is then swung down into the clip *j* again, and the end portion of the paper is laid against the outer side of said member and its edge portion is preferably folded over the edge of said member and pressed against the inner or concave side thereof, as also shown in Fig. 4. In this position of the parts, the tobacco may be readily placed on the paper, and the space

between the sections may be filled as full as may be necessary, as indicated in Fig. 4. The two sections are then closed together, compressing the tobacco therebetween, and leaving the end portion which was lying on the edge of section *a* projecting from between the sections, as in Fig. 5. This end portion is then moistened with the tongue and pressed down on the opposite portion of the paper which is lying in the outer side

85 of the member *h*, to which it will adhere, as indicated in the dotted line position of Fig. 5. This end portion is then moistened with the tongue and pressed down on the opposite portion of the paper which is lying in the outer side

90 of the member *h*, to which it will adhere, as indicated in the dotted line position of Fig. 5. The mold sections are then opened and the member *h* is swung up free of the clip *j*, so that the completed cigarette may then be withdrawn from said member *h*, as indicated in Fig. 8.

While the member *h* occupies some space within the formed cigarette, this member is in practice, made of thin metal and, if 100 the tobacco is well compressed, the expansion thereof will easily fill the narrow space caused by the withdrawal of the member, so that the loss in solidity is inappreciable, and a well-formed cigarette will be produced.

I claim:

1. A cigarette former comprising a pair of elongated, correspondingly shaped mold sections, pivotally connected at adjacent longitudinal edges and having transversely 110 concave molding faces, for the opposite sides of a cigarette, one of said sections

being longitudinally divided, to provide a main and a supplemental molding portion arranged to permit the cigarette paper to be passed therebetween and its end portions 5 overlapped and pressed against the exterior surface of the supplemental molding portion, to connect said end portions adhesively, and to permit the withdrawal of the finished cigarette from said supplemental 10 molding portion.

2. A cigarette former comprising a pair of elongated, transversely concave mold sections, pivotally connected at adjacent longitudinal edges and adapted to shape the opposite sides of a cigarette, one of said sections being longitudinally divided, intermediate its pivoted and free edges, into two molding portions connected at one end and constructed and arranged to permit the cigarette paper to be passed therebetween and its end portions to be overlapped and pressed against the outer side of the section adjacent its free edge, and the formed cigarette to be withdrawn longitudinally 20 at the opposite end when the mold sections are opened.

3. A cigarette former comprising a pair of elongated correspondingly shaped mold sections pivotally connected at adjacent longitudinal edges and having transversely concave molding faces, one of said sections being longitudinally divided from one end, intermediate its side edges, to provide a main member, which is directly connected 30 to the other section, and a supplemental member, means at the opposite end for normally holding said supplemental member in cigarette forming relation with the main member, and in position to permit one end 35 portion of the cigarette paper to be passed therebetween, the exterior of said supplemental member being constructed to permit the end portions of the paper to be overlapped thereon and pressed thereagainst, 40 to connect said end portions adhesively.

4. A cigarette former comprising a pair of similarly shaped mold sections pivotally connected at adjacent longitudinal edges, to permit the same to be swung toward and 45 from each other, one of said sections comprising a main member, to which the other

section is directly pivoted, and a supplemental member, forming a portion of the side of such section and extending throughout the length thereof and a pivot connecting one end of said supplemental member to the corresponding end of said main member, in position to permit the supplemental member to swing edgewise to and from the main member. 55

5. A cigarette former comprising a pair of similarly shaped mold sections pivotally connected at adjacent longitudinal edges, to permit the same to be swung toward and from each other, one of said sections comprising a main member, to which the other section is directly pivoted, and a supplemental member, forming a portion of the side of such section and extending throughout the length thereof, a pivot connecting 60 one end of said supplemental member to the corresponding end of said main member, in position to permit the supplemental member to swing edgewise to and from the main member, and a clip on the opposite end of 65 said main member arranged to receive the free end portion of said supplemental member and to hold the same in forming position. 70

6. A cigarette former comprising a pair of similarly shaped mold sections pivotally connected at adjacent longitudinal edges, to permit the same to be swung toward and from each other, one of said sections comprising a main member, to which the other 80 section is directly pivoted, and a supplemental member, forming a portion of the side of such section and extending throughout the length thereof and movable relative thereto in an edgewise direction, to permit 85 the cigarette paper to be placed in position within the mold and about said supplemental member and to permit the withdrawal of the formed cigarette therefrom, and walls at each end of said pivotally 90 connected sections arranged to close the ends of the mold when in open position and to overlap in the closed position thereof. 95

In testimony whereof, I have signed my name to this specification.

JAMES MacDONNELL.
